UNITED STATES PATENT OFFICE

HARRY RODSTEIN AND ISIDORE NATHANSON, OF BROOKLYN, NEW YORK

DESIGN FOR A GRILLE FOR A RADIATOR CABINET OR SIMILAR ARTICLE

Application filed March 19, 1931. Serial No. 39,167. Term of patent 7 years.

To all whom it may concern:

Be it known that HARRY RODSTEIN and ISIDORE NATHANSON, both citizens of the United States, and residents of Brooklyn, in the county of Kings and State of New York, have invented a new, original, and ornamental Design for a Grille for a Radiator Cabinet or Similar Article, of which the following is a specification, reference being had to the accompanying drawing, forming part thereof, in which the figure is a perspective view of a grille for a radiator cabinet embodying our new design.

We claim:

The ornamental design for a grille for a radiator cabinet or similar article, as shown. Dated, March 17th, 1931.

HARRY RODSTEIN.
ISIDORE NATHANSON.
